Filed Feb. 9, 1966, Ser. No. 526,293

6 Claims. (Cl. 220—26)

ABSTRACT OF THE DISCLOSURE

A secondary tank seal for a floating roof, the seal being flexible and joined to the flange of a movable shoe. One end of the flexible seal rides along the tank wall, and carries spring members which resiliently carry the seal over obstacles.

This invention generally concerns bulk storage tanks utilized to store petroleum products or the like, such tanks oftentimes having floating roofs or covers that raise with or float upon the fluid surface within the tank.

More particularly, this invention concerns an improved means for effecting a seal between the interior vertical wall of the tank and the peripheral edge of the roof or cover, and constitutes an improvement over presently pending application Ser. No. 445,919.

A major problem encountered in such floating-cover tanks, is the effecting of a seal between the cover and the inner periphery of the storage vessel, said cover necessarily having the smaller diameter in that it vertically moves within the confines of the vessel. Normally primary seal means have been provided which have included guide shoes attached to the cover with a flexible sheet joining the two, barring passage of fluids therebetween. Secondary seal means have been utilized to limit the passage of water downwardly through any space existing between the movable shoe and the interior vessel wall. Such a secondary seal is described in said earlier mentioned application. However, it has been found that such secondary seal means have tended to collect water in any space occurring between the vessel wall and any upwardly extending surface of the secondary seal, such water passing downwardly into the petroleum products between adjacent joints of the seal.

The secondary seal envisaged herein would include a flexible substantially crescent shaped member, attached to the movable shoe at one end, and having a sealing lip at the other end. A plurality of guide means are spaced around the edge of said member and, by extending outwardly thereof, tend to guide the sealing lip over rough spots occurring on the inner surface of the vessel wall. Such rough spots may be welds which tend to cause the secondary seal to become doubled up with resulting breakage of the seal and disengaging of the sealing member with a stiffening device provided thereto.

Thus, this invention has as its purpose the provision of a sealing means capable of preventing the flow of fluids into the inner cavity of a storage container.

A further object is the provision of means for guiding a sealing device over rough spots occurring on a container wall.

Yet another object is the provision of sealing means which may be expeditiously assembled and disassembled.

These and still other objects and capabilities should become apparent on considering the following appended description and drawings, in which:

FIGURE 1 is a partial perspective of the floating roof tank, showing one embodiment of the seal-guide;

FIGURE 2 is a cross section through the secondary seal showing one embodiment of the seal-guide;

FIGURE 3 is a cross section similar to FIGURE 2,

2

depicting the secondary seal affixed to the movable shoe, and having a stiffening member inserted in the seal;

FIGURE 4 is a perspective of an embodiment of the stiffening member;

FIGURE 5 is a cross section similar to FIGURE 3 showing a second embodiment of the seal-guide;

FIGURE 6 is a perspective of a seal-guide similar to that of FIGURE 5;

FIGURE 7 is a cross section similar to FIGURE 2 showing a further embodiment of the seal-guide, and

FIGURE 8 is a perspective of yet another embodiment of the seal-guide.

Looking first at FIGURE 1, a portion of an open-ended storage tank is generally shown by numeral 10, and includes upstanding wall 11.

Associated with the storage tank is a floating roof which is indicated by the numeral 20. This roof is designed to float upon the upper surface of the fluid contained within tank 10. The roof includes cover portion 21, bottom 22, these two members being connected or joined by plate 23. The space intermediate members 21, 22 and 23 may be subdivided by bulkheads such as 24.

A primary seal between the floating roof and wall 11 of tank 10 may be effected by vertically slidable shoes 30 which are associated with the floating roof by means of the hanger and balance structure generally indicated as 31, this latter structure being generally known, and not forming a part of this invention. A continuous flexible sheet material 32, would be secured to the roof and to the shoe, as at 33 and 34, respectively. Of course, grounding straps 35 may interconnect the roof and the primary seal. The upper edge of shoe structure 30 is shown to have an inturned flange 36, said flange coating with the secondary seal of this invention in a manner hereinafter described.

Moving now to FIGURES 2 and 3, one embodiment of the secondary seal comprising the critical element of this invention is shown, and illustrated generally by the numeral 40. Such a seal, while flexible, is shown to have a generally crescent shape, and includes a slot 41 at its lower end. This slot is utilized to envelop and clamp around in-turned lip or flange of shoe 30 when the secondary seal is affixed thereto. Such a clamping may be enhanced by means of insert 42 being positioned within cutout 43 which extends peripherally around seal 40 toward its lower end. Of course, after insertion of insert 42, additional rigidity may be provided by cementing it in place.

Central body portion 44 of seal 40, is relatively thin and flexible by virtue of wing-shaped cutaway portion which create down-turned lug portions 45, 46, which in turn define grooves 47, 48, respectively. Insertable within said cut-away portion is stiffening member 70, see FIGURES 3 and 4 especially. This member, while somewhat resilient, is less so than the material making up secondary seal 40. Further, member 70 may have an initial length somewhat greater than that between grooves 47, 48 so that on insertion therein, said stiffening member may bulge as shown in FIGURE 3. A plurality of such stiffening members 70 may be annularly spaced around the inner periphery of secondary seal 40, which seal forms a substantially continuous belt around the inside surface of vessel wall 11. Stiffening member 70 is shown to have oppositely positioned lips 71, 72, which lips fit snugly within grooves 47, 48 of seal 40. This coaction of lip-in-groove allows the stiffening member to be firmly placed.

The upper surface of secondary seal 40 defines a sealing lip 49, which lip slides along the inside surface of vessel wall 11, and may yieldingly pass over rough places existing in said wall. However, occasional structural features such as welds 12 or certain defects in wall 11 may exist which impede passage thereover, especially on an upward trip

of the secondary seal. This may cause severe bending of the secondary seal with resulting dislocation of the stiffening member 70 and even a loss of the sealing effect. Therefore, this invention contemplates the use of a guide means which will, in effect, permit the passage of the sealing lip 49 over such danger areas. One embodiment of such a guide is shown in FIGURES 2 and 3, and comprises a plurality of spaced spring-like structures 80. Each of said springs may have its shank 81 imbedded in and/or affixed, as by cementing, a recess provided in secondary seal 40. The head 82 may be bent so as to present a curved surface which may normally pass closely adjacent the vessel wall 11 in advance of sealing lip 49 during its upward journey. Thus, on sealing lip 49 encountering a feature such as weld 12, sealing lip 49 will tend to be restrained and the secondary seal will bend. At this time, guide 80 will be pressed against wall 11 and inasmuch as guide 80 is sufficiently less resilient than seal 40 it therefore presents a greater force of resistance to any tendency of seal 40 to be bent and in effect pushes lip 49 radially inward out of the path of the impediment until it passes same and can return to contact the vessel wall.

A second embodiment of the guide means of this invention is shown in FIGURES 5 and 6 and represented generally by 80a. This guide also includes a shank 81a, which passes through a recess 83a that passes through seal 40 from a position near sealing lip 49 to exit in the area defined by groove 47. Spaced inwardly from end 84a of shank 81a, is a cross-piece or support 85a, which is securely affixed to shank 81a, and not only increases the rigidity of the guide, but permits it to be securely positioned with respect to seal 40, provides ease of assembly by inserting head portion 82a, through aperture 83a of the seal until cross-piece 85a reaches the upward limit of groove 47 and resists any tendency of the guide to twist or turn on encountering any barrier. The cross-piece may be positioned outwardly of the stiffening member 70 within space 73, as shown in FIGURE 5, or, their respective positions may be reversed by placing opposite ends of the cross-piece 85a intermediate lip 71 of stiffener 70 and aperture 83a. In either case, both the stiffening member and the guide may be securely positioned. It may be desirable, after assembly to cement, or otherwise unify the juncture of the stiffening lip, such as 71, cross-piece 85a and lug, such as 45. This latter embodiment, while functioning in the same manner as that shown in FIGURES 2 and 3 provides the added benefit of ease of inserting the head through the seal, and of more securely unifying the guide to the seal preventing rotation or twisting of the guide with respect to the seal.

FIGURE 6 includes a loop or finger piece 84a facilitating ease of insertion and removal of the guide into and from aperture 83a.

In the further embodiment of FIGURE 7, cross-piece B5b is placed outside and adjacent the guide rather than within groove 47. This not only permits ease of assembly, but also inasmuch as the greatest force is exerted against the seal during the upward journey, this configuration resists any tendency to force the guide shank back through the secondary seal body.

In the embodiment of FIGURE 8, struts 90 are provided to opposite ends of cross-piece 85c to further resist any tendency to turn or twist and a bent end 91 is provided permitting ease of inserting the head through aperture 83a.

At this point it should be noted that a plurality of seal guides are spaced around the periphery of the secondary seal, each of said guides independently functioning. Thus, if damage occurs to one or more of such guides, the remaining guides may continue to function without deterring the overall sealing effect.

While only limited embodiments of this invention have been described, it should be apparent that numerous modi-

fications might be possible by one skilled in the art without departing from the spirit of this invention, the scope of which is only intended to be limited by the following appended claims.

What is claimed is:

1. An improved secondary seal for use with a floating roof in a storage tank, the roof being of the type having a primary seal shoe vertically slideable along the tank wall, the improved seal comprising:

a flexible annular body portion, one edge of which is joined to said shoe, and the opposite edge of which forms a wall engaging portion; and
guide means fixed to said body portion adjacent said wall engaging portion and extending axially upward therefrom so as to guide said seal over obstacles present in said tank wall, said guide means comprising a plurality of elongated spring elements each having one end extending through an aperture provided in said body portion adjacent said wall engaging portion.

2. The device of claim 1 wherein said body portion includes a recess in its radially inward side, and said spring includes a cross bar positioned within said body portion recess for resisting slippage of said spring relative to said body portion.

3. A secondary seal for use with a floating roof and movable primary seal shoe arrangement in a storage vessel, the seal including:

a flexible annular member having a generally crescent shaped radial cross section;
thickened portions adjacent the upper and lower edges of said annular member;
grooves provided in each of said thickened portions, said grooves generally facing each other;
one of said thickened portions being clamped about a radially inturned lip of said shoe;
the other of said thickened portions including a wall-engaging sealing lip;
stiffener means having opposite edges which are inserted within said grooves; and
guiding means joined to said annular member adjacent said upper edge and extending axially outward therefrom adapted to guide said seal over obstacles in the wall of said storage vessel, said guiding means comprising a plurality of elongated springs each having one end embedded in said annular member.

4. The seal of claim 3 and including passageways through said upper thickened portion and communicating with said upper groove, a portion of each of said elongated spring guiding means being inserted within said passageway.

5. The seal of claim 4 wherein said guiding means includes a cross bar within the upper of said grooves for resisting slippage of said guiding means relative to said annular member.

6. The seal of claim 4 wherein said guiding means includes grasping means at one end for facilitating ease of inserting and removing said guiding means into and from said passageway.
